DISPLAY RACK

Cedric Seaman, Rye, N. Y., assignor to Bakeries Service Corporation, a corporation of Delaware

Application July 6, 1932. Serial No. 621,015

2 Claims. (Cl. 211—184)

This invention relates to improvements in display racks particularly suited to counter-display of such things as wrapped loaves of bread, cake, and the like.

5 Among other objects, the invention is intended to supply a compact, inexpensive and simple construction of rack which will adequately hold the merchandise to be displayed, while at the same time leaving exposed, in large degree, to enhance 10 the display effect, the merchandise and its wrappings, and such trade-mark and advertising material as may be exhibited on the wrappings. Furthermore, the invention contemplates a sectional or extensible rack such that a plurality 15 of rack-units may be readily coupled together to form a substantially integrated structure appropriate to whatever volume of merchandise is desired to be displayed.

An illustrative embodiment of the invention is 20 shown in the accompanying drawing in which,—

Fig. 1 is a perspective of a rack comprising two illustrative units, and

Fig. 2 is a detail section, on an enlarged scale, through the line 2—2 of Fig. 1.

25 One of the rack units comprises a preferably narrow metal strip 3 bent in U-shape, and a corresponding similarly bent narrow strip 4. These strips 3 and 4 are secured in spaced relationship by transverse bars 5, 6, which may be spot-welded, 30 brazed or otherwise secured to the strips 3 and 4; and also by transverse members 7, 8 similarly secured to the strips 3 and 4.

The dimensions and character of the metal strips 3 and 4 are such that the vertically disposed 35 legs of the U-shaped frame are relatively flexible or "springy", in sufficient degree to avoid too great pressure upon soft bread or the like which may be forced between the rack legs. Loaves of bread or the like, from the same batch, vary considerably in size, although intended to be of uniform dimensions; and the flexibility of the rack legs permits loaves to be interposed between the rack legs in whatever tight fit may occur, without material danger of mutilating the loaves or their 45 wrappers.

At the same time, when numerous loaves are closely packed between the rack legs, the flexibility of the latter tends to hold the loaves securely in position. At the same time, while the small 50 cross-sections of the strips 3 and 4 contribute to their easy flexibility, the loaves and their wrappers are left exposed in very large degree so that the display material thereon is readily observable both at the ends and sides of the loaves. 55 When more than one rack-unit is employed (as

presently described) the sides of loaves in the second unit are exposed even though the loaves in the second unit may obscure the sides of the loaves in the first unit.

The above described U-shaped unit serves as a 60 primary unit in an extensible or sectional rack; and a second and similar unit may be provided by strips 9 and 10 bent in an L-shape and secured together by transverse strips 11, 12 and 13.

The secondary unit comprising the strips 9 65 and 10 may be substantially integrated with the primary unit comprising the strips 3 and 4. A simple preferred means of doing this is shown in the drawing. The transverse strip 8 of the primary unit is formed with a horizontally extending 70 flange 14 which may be exactly like the flange 15 of the strip 12 shown at the right-hand extremity of Fig. 1. The flange 14 has two lugs 16 struck up from its surface, and before the assembly of the two units is completed the lugs 16 75 stand in the upright position indicated by the lugs 17, 17 on flange 15. To receive the lugs 16, 16 (which are part of the primary unit), the transverse strip 13 (of the secondary unit) is provided with two slots such as are indicated (at 80 the right of Fig. 2) in the transverse strip 18 of a detached, hypothetical third unit similar to the second unit comprising the strips 9 and 10. In assembling one unit with another, the slots are fitted upon the upstanding lugs, and then, merely 85 by a tap of the hammer, each lug may be bent down to lock the two units together.

Starting with a primary unit like that comprising the strips 3 and 4, additional units (like that comprising strips 9 and 10) may be added so 90 far as desired.

The same character of relative flexibility above referred to inheres in the relationship between the vertical legs of the strips 9 and 10 and the adjacent vertical legs of strips 3 and 4. Although the horizontal bases of the two units may be secured rigidly together by the described lug-and-slot arrangement, nevertheless the upstanding legs at the opposite ends of the unit will be 95 relatively flexible for the purposes already explained.

Once two or more rack units have been secured together, they may be readily detached from each other by simply prying up the lugs 16, 16 with a screw driver so that they resume 105 the upstanding position of the lugs 17, 17. Thereupon the slotted strip previously secured by the lugs may be simply lifted off and the corresponding rack unit may be removed.

I claim:

1. A display rack comprising in combination, a primary unit consisting of U-shaped thin and narrow metal strips arranged to rest upon their horizontal bases and to have vertically upstanding legs, the legs of each strip being disconnected from each other except at their bases; transverse strips connecting the upstanding legs of the respective U-shaped strips to form a rack unit having sides which are relatively flexible; a second rack unit consisting of L-shaped thin and narrow metal strips arranged to rest upon a horizontal base and to have upstanding legs flexible in relation to the legs of the primary unit, and having also transverse strips to secure together the respective L-shaped strips; and detachable means for securing the primary unit

and the second unit together with substantial rigidity, while leaving the upstanding legs relatively flexible.

2. A display rack as described in claim 1 in which the detachable means for securing the primary and second units together, are characterized by having a horizontally disposed plate secured to one unit, overlying a similar plate secured to the other unit, one said plate having bendable lugs projecting through slots in the other said plate and constructed to be bent down toward the latter plate to hold the two plates and the respective units together with substantial rigidity.
